assignors to Lucerne Products, Inc., Northfield, Ohio,
a corporation of Ohio

Filed June 10, 1959, Ser. No. 56,302

Term of patent 14 years

(Cl. D62—2)

Fig. 1 is a front perspective view showing the right side of a spray gun attachment for vacuum cleaners embodying our new design, the broken-line representation of a jar being shown for illustrative purposes only;

Fig. 2 is a rear perspective view thereof showing the right side thereof, the left side not shown being substantially the same as the right side shown;

Fig. 3 is a top plan view thereof;

Fig. 4 is a fragmentary front elevational view thereof; and

Fig. 5 is a fragmentary rear elevational view thereof.

The broken line representation of a container in Fig. 1 and of a container cap in the several views is shown for illustrative purposes only.

The dominant features of my design reside in the full line portions of the drawing.

We claim:

The ornamental design for a spray gun attachment for vacuum cleaners, as shown and described.
